UNITED STATES PATENT OFFICE.

JOEL U. ADAMS, OF CINCINNATI, OHIO

TRUSS-PAD.

1,098,546.

Specification of Letters Patent.

Patented June 2, 1914.

Application filed September 2, 1913. Serial No. 787,614.

To all whom it may concern:

Be it known that I, JOEL U. ADAMS, a citizen of the United States, and residing at Cincinnati, Hamilton county, State of Ohio, have invented certain new and useful Improvements in Truss-Pads; and I do declare the following to be a clear, full, and exact description of the invention, attention being called to the drawing which accompanies this application and forms a part thereof.

This invention concerns truss-pads and relates to the construction of such pads as the same is hereinafter described and claimed and as illustrated in the accompanying drawing, in which:

Figure 1, shows the back side of the pad, that is the side opposite to the side which comes in contact with the wearer. Fig. 2, is a central longitudinal section of the pad. Fig. 3, shows the pad as viewed in Fig. 1, but with the back-plate of same removed. Fig. 4, shows a vertical cross-section through a member forming the inclosure of the body 25 of the pad. Fig. 5, in a view similar to Fig. 1, illustrates certain modified features. Fig. 6, is a side-elevation of the pad as shown in Fig. 5, and partly in section.

The body of the pad is made of material 30 A, suitable for the purpose and selected according to any particular cushioning effect which may be desired. This material is contained in a pouch-shaped cover of elastic material like rubber which is so formed as 35 to produce the rounded and convex face or contact-portion B, meaning thereby that portion which comes in contact with the skin of the user, and the flat and annular back portion b, which borders the open portion 40 of the pouch through which the filling material is introduced.

A properly shaped plate C, is placed upon the filling and held in position by being forced under the annular portion b, of the pouch. The back of the pad consists of a plate D, similar in shape to plate C, and incased by a cover E, of a material similar to that of the pouch. This cover extends around the edge of plate D, and by overlapping 45 the same on its underside, as shown at e, is thereby securely held in place.

One or more holes c, to receive one or more screws, are provided in plate C, and similar holes d, are provided in plate D, 50 which register with holes c.

Screws 8, are used to secure the back to

plate C, with the edge b, of the pouch and the edge e, of cover E superposed and in contact with each other and clamped between the two plates. The body of the pad 60 is thus completed in a substantial manner and with the covering thereof held firmly in position without the use of stitches, glue or cement.

The pad is secured to a belt or other 65 means whereby it is held in position, by suitable devices as for instance by a shank 10, which is perforated for the reception of attaching means.

Screws 8, serve readily for this purpose, so 70 that one screw-connection may be used to connect face and back parts of the pad to each other and the complete pad in its entirety to the shank. The connection to this latter may also be one which permits rotary 75 adjustment about the point of connection, to permit change of the angular relation of the pad with reference to the shank as indicated in Fig. 5. For this purpose a circular disk 11, is used and held in place by a 80 cap F, which has a central circular opening, somewhat smaller than the disk. The edge around this opening is shaped to extend over the edge of the disk, as shown at 12, so as to hold the same in place, while permitting it to rotate. The cap is provided with flanges 13, whereby it is attached to the back of the pad by screws 14, being seated in plate D. Screws 15 engage the shank and are seated in the disk and when said screws 90 are tightened, shank and disk are closely drawn together, clamping the inturned edge 12 of the cap between them. The pad is thus rigidly held to the shank.

Having described my invention, I claim 95 as new:

1. A pad consisting of a pouch-shaped cover of elastic material, suitable filling material contained therein, a plate held in place on top of the filling material by the overlapping edge of the pouch under which said plate is slipped, a back plate similar to the plate first mentioned, an elastic casing for the same held in place by its edge which overlaps said back plate on its underside and 100 contacts with the inturned edge of the pouch and a screw passing through this covering and through the back plate below it and seated in the plate first mentioned whereby the two plates are held to each other and 105 whereby the contacting edges of the pouch and the covering of the back-plate are held 110

in position by the clamping action of said two plates.

2. A pad consisting of a face-portion and a back-portion, each comprising an elastic covering and a plate, the edges of the coverings overlapping the edges of the respective plates and contacting with each other, a shank on which the pad is supported and a screw adapted to engage this shank and the respective plates and seated in the plate of the face-portion of the pad, to hold this lat-

ter to the back-portion thereof so as to clamp the contacting edges of the coverings in position and to hold the pad in its entirety to the shank.

15

In testimony whereof, I hereunto affix my signature in the presence of two witnesses.

JOEL U. ADAMS.

Witnesses:

GEO. E. BAILEY,
C. SPENGEL.
